UNITED STATES PATENT OFFICE.

CHARLES HOWARD SMITH, OF SHORT HILLS, AND EDWARD B. EDWARDS, OF EAST ORANGE, NEW JERSEY, ASSIGNEES TO INTERNATIONAL COAL PRODUCTS CORPORATION, OF RICHMOND, VIRGINIA, A CORPORATION OF VIRGINIA.

FURNACE RETORT.

1,417,113.

Specification of Letters Patent. Patented May 23, 1922.

Application filed June 10, 1919. Serial No. 303,222.

To all whom it may concern:

Be it known that we, CHARLES H. SMITH, a citizen of the United States, and EDWARD B. EDWARDS, a subject of the King of England, (who has forsaken his allegiance to said country and has taken oath declaring his intention of becoming a citizen of the United States,) and residents, respectively, of Short Hills, county of Essex, State of 10 New Jersey, and East Orange, county of Essex, State of New Jersey, have made certain new and useful Improvements in Furnace Retorts, of which the following is a specification.

15 The invention relates to furnace-retorts and involves a construction having a retort with mixing and conveying means therein, a furnace constructed for exteriorly heating the retort, and a regenerator arranged in 20 association with the furnace in such a manner that the air for supporting combustion in the combustion chamber or combustion spaces is heated by passing inwardly at one 25 interval through a portion of the regenerator through which during the previous interval the products of combustion passed outwardly.

A construction wherein the invention is realized is shown in the accompanying 30 drawings forming a part of this specification, and in which drawings—

Figure 1 is a vertical longitudinal section of a furnace-retort having a regenerator. This figure is a view taken as on the broken 35 line 1—1 of Figure 2 looking in the direction of the arrows. In this figure there are also shown burners having pipes through which fuel, as gas, is supplied to the combustion chamber or combustion spaces of the 40 furnace.

Figure 2 is a vertical transverse sectional view taken as on the plane indicated by the line 2—2 of Figure 1 looking in the direction of the arrows.

45 Figure 3 is a view diagrammatically illustrating the manner in which the air for supporting combustion, and which air is pre-heated by a regenerator portion, passes from the regenerator portion to the burner of the 50 combustion chamber or combustion spaces—or in other words to the burners supplying fuel to the chamber or spaces. This figure also diagrammatically illustrates the manner in which the products of combustion

pass from the combustion chamber or combustion spaces to another portion of the regenerator. It also clearly indicates the manner in which the operations can be reversed whereby at one interval the products of combustion pass outwardly through a particular 55 portion of the retort and whereby at the succeeding interval the air passes inwardly through the same portion.

Referring now to the drawings in detail it will be seen that there is shown therein 60 a combined furnace and retort frequently referred to as a furnace-retort; there is also shown below the retort and furnace proper a regenerator in association therewith. The 65 retort proper is designated by 1 and has a longitudinally extending tubular inner wall or retort shell 2 closed at each end thereof by suitable heads, designated 3 and 4. The head 3 is located at what is known as the charging end of the retort and coal or other 70 carbonaceous material is fed into the retort by feeding or charging means, as 5, which in the form shown is indicated as having a hopper 6 and screw-feed 7. Within the retort there are located parallel shafts 8 carrying 75 paddles 9 thereupon, which shafts and paddles constitute means for mixing or agitating the material within the retort and for conveying it from the charging end of the retort toward the discharging end thereof. 80 The retort is exteriorly heated and the gases and vapors driven off during the heating are conducted from the interior of the retort by means of piping 10. Suitable means, as 11, is provided whereby the material can 85 be periodically discharged from the retort without permitting the entrance of any substantial amount of air thereinto.

The construction of the retort is such that it is practically air-tight whereby no substantial amount of air enters the retort when being operated and whereby practically no gases leave or escape from the retort, except through piping 10. The furnace portion of the furnace-retort is constructed so 95 as to provide a combustion chamber 12 which includes the combustion chamber 13 at the right hand side or longitudinal half of the furnace and the combustion chamber 14 at the left hand side or longitudinal half of 100 the furnace (see Fig. 2). In other words, the combustion chamber 12 may be considered to be divided by two vertically and 105

longitudinally extending partitions 15 and 16 into the smaller right and left hand combustion chambers 13 and 14. The structure at the right hand side or longitudinal half 5 of the furnace is the same as the structure at the left hand side or longitudinal half of the furnace and hence a description of one portion will suffice. The combustion chamber 13 is divided by vertically and trans- 10 versely extending partitions 17 into two sets of combustion spaces, the combustion spaces of one set being designated by 18 and the combustion spaces of the other set by 19. Each combustion space (18 or 19 as the case 15 may be) is located both below and at the outside of the retort or retort shell. A horizontally, transversely and longitudinally extending partition 20 caps the vertically and transversely extending partitions 17 and 20 the uppermost exterior portion of the retort shell and there is left a space above the partition 20. This space above the partition 20 is in fact a longitudinal flue (at the right or left hand side of the furnace as the case 25 may be) above the combustion spaces and the retort itself. The partition 20 is provided with openings 21 each of which openings is controlled by a damper 22, there being an opening corresponding to each of 30 the combustion spaces, 18, 19, whereby the combustion spaces of one set can be in communication with the combustion spaces of the other set through the longitudinal flue above the combustion spaces.

35 A piping 23 is provided which includes a three-way valve 24 and two main branch pipes 25 and 26. This three-way valve 24 is constructed so that it can cut off the supply to both of the branch pipes 25, 26, or 40 so that it can supply one or the other of the branch pipes but so that it cannot supply both at the same time. Small branch pipes 27, each having a valve 27', lead from the main branch pipe 25 to the combustion 45 spaces 18, while other branch pipes 28, each having a valve 28', lead from the main branch pipe 26 to the combustion spaces 19 whereby, dependent upon which of the main branch pipes is open, fuel is supplied to the 50 interior of the set of combustion spaces 18 or 19. In the masonry of each side or longitudinal half of the furnace there are provided two longitudinally extending main flues, designated as 29 and 30 respectively. 55 The masonry of each side or longitudinal half of the furnace is also provided with two regenerator portions 31 and 32. Regenerator portion 31 is in communication with main flue 29 by means of passageway 33 and the regenerator portion 32 is in communication with the main flue 30 by means of the passageway 34, which passageways 33 and 34 may each be considered as extending between one of the longitudinally extending 60 main flues on the one hand and its cor-

responding regenerator portion on the other. A passageway, as 35, extends between the main flue 29 on the one hand and the lower portion of each of the combustion spaces 18 of the set corresponding thereto on the other, while a passageway as 36 extends between the main flue 30 on the one hand and the lower portion of each of the combustion spaces 19 of the set corresponding thereto on the other. The passageways 75 35 and 36 have dampers, 37 and 38, for controlling or regulating the flow therethrough. Each of the regenerator portions has an inlet 39 which can be open or closed, or, in other words, controlled by a damper or valve 80 40, and each of the regenerator portions also has an outlet 41 controlled by a damper or valve 42; each of the outlets leads to a waste heat flue 43 for conducting waste gases to a stack 44.

85

The operating of the heating system in the furnace-retort may be conducted as follows:

With the air inlet open and the outlet closed of regenerator portion 31 and with the air inlet closed and the outlet open of regenerator portion 32, it will be observed that air enters the regenerator portion 31—which may be arbitrarily referred to as regenerator portion A—passes therethrough, 90 then through passageway 33 into the longitudinally extending main flue 29; thence flows through the damper controlled passageways 35 into half of the combustion spaces which are arranged along and on the 100 exterior of the retort, to wit, the set of combustion spaces 18, wherein combustion takes place due to the igniting of the fuel which is supplied to said spaces when air which has been preheated in the regenerator portion A is supplied thereto. The set of combustion spaces 18 may be arbitrarily referred to as combustion spaces A, at this time fuel being supplied to those spaces A. The products of combustion then pass 105 through openings 21 into the longitudinal flue above the combustion spaces and from said longitudinal flue into and through the other half of the combustion spaces, to wit, the combustion spaces 19 constituting the 110 other set, and this set of spaces may be arbitrarily referred to as combustion spaces B.

115

The terming of the set of combustion spaces 18 and of the set of combustion spaces 19 as combustion spaces A and combustion spaces B is justifiable because the combustion spaces may be considered as a whole to constitute or include a number of smaller combustion spaces. These combustion spaces 125 A and B may in a still broader sense be considered to constitute a part of a combustion chamber.

From the combustion spaces 19—combustion space or spaces B—the products of com- 130

- bustion flow through the damper controlled passageways 36 to the longitudinally extending main flue, to wit, main flue 30, thence through passageway 35 into and through the 5 regenerator portion 32, which portion may be arbitrarily designated as the regenerator portion B, and finally therefrom through the damper controlled outlet 41 to the waste heat flue 43.
- 10 It will here be remarked that with equal propriety the regenerator portion 32 could have been referred to as regenerator A, that the set of combustion spaces 19 could have been referred to as combustion spaces A, 15 that the set of combustion spaces 18 could have been referred to as combustion spaces B and that the regenerator portion 31 could have been referred to as regenerator B. These nomenclatures have been adopted to 20 facilitate the following of the operation and particularly in connection with some of the claims, it being understood that this designation is not to be construed in a limiting sense but merely to indicate or facilitate 25 the following of the steps recited.
- The steps above described in detail are carried out at one interval in one series through the regenerator and furnace and in a succeeding interval in a reverse series 30 through the regenerator and furnace, this being done by closing the air inlet 39 of regenerator 31 or regenerator A, by opening the outlet 41 of the same regenerator portion, by closing the outlet 41 of regenerator portion 32 or regenerator B, and by opening 35 the inlet of said regenerator portion; also by changing the fuel supply; or, in other words, the fuel supply is cut off from branch pipe 25 and is allowed or caused to pass to main 40 branch pipe 26 and therefrom into the set of combustion spaces 19—set B. When this condition exists the incoming air passes into and through regenerator portion B, thence into combustion spaces of set B wherein 45 combustion takes place; the products of combustion then pass into the combustion spaces of set A, therefrom into and through regenerator portion A, finally leaving the open outlet to regenerator portion A leading 50 to the waste heat flue 43.
- It will also be noted that the construction is such that the cycle of operation herein described can be successively and repeatedly carried out.
- 55 The invention is not limited to the specific construction and arrangement shown and described, as it may be embodied in various forms and modifications without departing from the spirit and scope thereof.
- 60 What is claimed is:
1. A furnace-retort construction having a longitudinally extending retort shell, combustion spaces exteriorly arranged along and on opposite sides of the longitudinally extending retort shell, each of which combustion spaces is located both below and at a side of the retort shell, burners for supplying fuel to the interior of the combustion spaces in a manner whereby alternate combustion spaces along each longitudinal half of the retort will receive fuel at a time when the other combustion spaces are serving as flues through which the products of combustion can pass on their way from the combustion spaces to which the fuel is being supplied, a longitudinally extending flue above the retort itself and the combustion spaces at the side of the retort, each combustion space being in communication with the said longitudinally extending flue above it, main flues, 70 a passageway extending between each of the combustion spaces and a main flue corresponding to the combustion space, and a regenerator, the construction being such that at one interval combustion is taking place in one half of the combustion spaces being supported by air flowing inwardly through one portion of the regenerator and so that at the same time the products of combustion are passing into and from the other half of the combustion spaces, thence inwardly through another portion of the regenerator, the construction also being such that these conditions can be successively reversed. 75
  2. A furnace-retort the furnace of which has a combustion chamber that is divided into two sets of combustion spaces arranged for exteriorly heating the retort, the furnace-retort having a regenerator divided into two regenerator portions one portion corresponding to one set of said combustion spaces and the other portion corresponding to the other set of said combustion spaces, the furnace-retort construction being such that the combustion spaces each extend both below and at a side of the furnace-retort and so that at each side of the furnace-retort there is a longitudinally extending flue above the combustion spaces and the retorts itself, the furnace-retort construction also being such that there is provided a main flue, or flues, corresponding to one set of the combustion spaces and one of the regenerator portions, and another flue, or flues, corresponding to the other set of combustion spaces and the other regenerator portion, the furnace also having two sets of gas burners, a set for and corresponding to each set of combustion spaces and the corresponding regenerator portion, there being a burner for each combustion space and a passageway extending between each combustion space and its corresponding main flue, there also being a passageway between each regenerator portion and main flue corresponding thereto. 100
  3. A furnace-retort construction having a longitudinally extending retort shell, two sets of combustion spaces on the exterior of the retort shell, piping for supplying fuel at 105

one interval to the interior of one of said combustion spaces and for supplying fuel at a subsequent interval to the other of said combustion spaces, a regenerator having two 5 portions, two passageways one corresponding to one of the combustion spaces and extending between one of the regenerator portions and the combustion space corresponding thereto, the other corresponding to the 10 other combustion space and extending between it and the other regenerator portion which corresponds thereto, the combustion spaces each being located both below and 15 at the sides of the retort shell, the furnace-retort construction also providing a longitudinal flue above the two sets of combustion spaces and the retort shell.

4. A furnace-retort having a longitudinally extending retort shell and two sets of 20 combustion spaces located both below and at the sides of the retort shell, and burners for supplying fuel to the interior of the combustion spaces so that one set of combustion spaces receives fuel while the other set serves 25 as flues through which products of combustion pass on their way from the set of combustion spaces receiving fuel, the furnace-retort being constructed so that there is provided a longitudinal flue above the combustion spaces and the retort shell, each combustion space being in communication with

said last mentioned flue, the furnace-retort also having two main flues, passageways extending between the lower portion of one set of the combustion spaces and one of the 35 main flues, and passageways extending between the lower portion of the other set and the other main flue, air at one interval passing from one of the main flues through the corresponding passageway to one set of the 40 combustion spaces, wherein combustion takes place, and from which set the products of combustion pass into the longitudinal flue above the combustion spaces then from said last mentioned flue into the other set, thence 45 through the passageways leading therefrom to the other main flue.

5. A furnace retort having a longitudinally extending retort shell and two sets of 50 combustion spaces which are located both below and at the sides of the retort, burners for supplying fuel to the interior of the combustion spaces and longitudinal flues above the combustion spaces and the retort itself, each of which combustion spaces is 55 in communication with the longitudinal flue above it.

This specification signed the 23rd day of May, 1919.

CHARLES HOWARD SMITH.
EDWARD B. EDWARDS.
